(71) Applicant: **Robert Banik**, Hollywood, FL (US)

(72) Inventor: **Robert Banik**, Hollywood, FL (US)

(73) Assignee: **International Medical Industries, Inc.**,
Pompano Beach (UZ)

(**) Term: **15 Years**

(21) Appl. No.: **29/704,234**

(22) Filed: **Sep. 3, 2019**

(51) LOC (13) Cl. **24-02**

(52) U.S. Cl.

USPC **D24/130**

Jennie S. Malloy

(57) **CLAIM**

The ornamental design for an asymmetrical self-righting tip cap, as shown and described.

DESCRIPTION

FIG. 1 is a front perspective view for an asymmetrical self-righting tip cap;

FIG. 2 is a rear perspective view thereof;

FIG. 3 is a front elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear elevational view thereof.

The broken lines show portions of the asymmetrical self-righting tip cap that form no part of the claimed design.

1 Claim, 8 Drawing Sheets
